J. W. RYAN

PLIERS

Filed Dec. 1, 1926

INVENTOR.
J.W.Ryan

BY George J. DeMolte
ATTORNEY

UNITED STATES PATENT OFFICE.

JOHN W. RYAN, OF FRENCH CAMP, CALIFORNIA.

PLIERS.

Application filed December 1, 1926, Serial No. 151,899.

This invention relates to improvements in pliers such as are commonly used for gripping and turning small pins, rods, nuts and the like. As such pliers are usually constructed it is a hard manner to keep the jaws from slipping on the part being gripped when a turning pressure is applied to the handles; and great handle contracting pressure, calling for the use of considerable physical strength, is therefore necessary to prevent such slipping.

The principal object of my invention therefore is to avoid this defect in operation by constructing the pliers in such a manner that when the handles are contracted after the jaws have engaged an object, said jaws will be brought into gripping engagement with the object with a force much greater in proportion to that used in contracting the handles, or which is obtainable with ordinary pliers. In other words additional or boosting leverage means has been placed between the handle and the jaws, operable when the handles are contracted and the jaws resist closing movement, which increases the force tending to close the jaws without the use of very heavy pressure on the handles, and without making the handles of an excessive length.

These parts are so arranged that this additional leverage or force functions automatically whenever the handles are contracted and pressure is applied in the usual manner to turn the object being gripped by the pliers. No manual adjustments are therefore necessary to cause the pliers to thus function, and the gripping pressure of the jaws will be instantly and automatically released as soon as the contracting pressure on the handles is released and they are allowed to spread.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved pliers as engaged with a nut but before the handles are contracted to cause the gripping

pressure on the jaws to be brought into operation.

Fig. 2 is a similar view of the pliers after the handles are contracted and the jaws gripped against the nut.

Fig. 3 is a fragmentary cross section on the line 3-3 of Fig. 2.

Referring now more particularly to the characters of reference on the drawings, the device comprises a pair of opposed jaws 1 of the usual character having at their inner ends bosses or hubs 2 which are superimposed on each other and pivoted together by a rivet 3 or the like. From the sides of the hubs opposite to the jaws and in the reverse relation to the position of the jaws on the hubs, short arms 4 project. Pivoted onto these arms and forming extensions thereof are opposed spreading handles 5, the pivotal connections being indicated at 5^a. Shoulders 6 between the handles and arms prevent outward movement of the handles relative to the arms beyond a certain limit, while allowing for the inward turning movement of the handles on the pivots. These parts are so arranged as in all pliers that when the handles are separated the jaws are also separated, and vice versa.

Projecting from the hubs 2 in the same general direction as the arms 4 and therebetween are lugs 7. The two lugs are necessarily offset from each other transversely but their relatively adjacent transverse faces are so disposed relative to each other as to form a V-shaped transversely extending opening 8 therebetween, said opening being symmetrically disposed relative to the longitudinal axis of the pliers and the apex thereof facing the pivot 3.

Fitting in the opening 8 and having a width sufficient to engage both said adjacent faces of the lugs 7 is a wedge shaped block 9. The outer end of this block is pivoted in common onto a pair of links 10 which extend thence at an acute angle toward the outer ends of the handles to pivotal connections with said handles a short distance from the pivots 5^a. In order to prevent possible lateral movement of the block relative to the lugs, the co-acting faces of these parts are longitudinally tongued and grooved as shown at 11.

In operation the pliers are manipulated in the usual manner in order to enable the jaws to be engaged with a nut 12 or other part

to be turned. When spreading the jaws the shoulders 6 engage so that the handles 5 and the arms 4 are rigid from end to end and move as a unit. When contracting the handles without any pressure being on the jaws to resist their closing the shoulders will still remain practically engaged, since the pivots 5^a are tight enough to prevent turning of the handles relative to the arms under the 10 above conditions. When, however, the jaws are engaged with a nut and contracting pressure is placed on the handles to cause the jaws to grip the nut, the resistance to closing of the jaws causes the handles to turn 15 on their pivots 5^a. This movement in turn causes the block 9 to be moved toward the jaws as will be evident, and in so doing said block will move further into the opening 8 and will spread the lugs 7. This spreading 20 of the lugs imparts a closing action to the jaws. The latter will be then firmly gripped against the nut, and when a rotative pressure is imparted to the pliers, with the neutral contracting pressure being maintained 25 on the handles while so doing, said jaws will not have any tendency to slip on the nut or separate. This is because the leverage force between the handles and the jaws is increased considerably by the interposition of 30 the wedge block.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit 40 of the invention, as defined by the appended claims.

Having thus described my invention what I claim as new and useful and desire to secure by Letters Patent is:

45 1. A pliers comprising a pair of opposed jaw and handle members pivoted together intermediate their ends and arranged to cause a contracting movement of the handles to normally impart a closing movement to the jaws, and means between the handle members and jaws for increasing the force tending to close the jaws when the handles are contracted.

55 2. A pliers comprising a pair of opposed jaw and handle members pivoted together intermediate their ends and arranged to cause a contracting movement of the handles to impart a direct closing movement to the jaws when the latter are free of any movement-resisting influence, and means between

the handle members and jaws for increasing the leverage tending to close the jaws when the jaws are engaged with an object and resist closing movement.

65 3. A pliers comprising a pair of opposed jaw and handle members pivoted together intermediate their ends and arranged to cause a contracting movement of the handles to normally impart a closing movement to the jaws, one of said handle members having an inwardly breaking pivoted joint intermediate its ends, and leverage increasing means between the handle members outwardly of the pivoted point and the jaws for imparting a closing movement to the 75 jaws when said handle member breaks at said joint.

4. A pliers comprising a pair of opposed jaws, a pivot connecting the same, opposed handle members for operating the jaws comprising arms rigid with the jaws and handles extending beyond and pivoted onto the arms, opposed lugs formed rigid with the arms and jaws and projecting away from the jaws and disposed between the arms, the adjacent transversely extending faces of the lugs being disposed at an acute angle to each other, a wedge block to fit between and engage said faces, and links connecting the block to the handles intermediate their ends.

5. A pliers comprising a pair of opposed jaws, a pivot connecting the same, opposed handle members for operating the jaws, opposed lugs formed rigid with the jaws and projecting beyond the jaw pivot in a direction opposite to the jaws, the adjacent transversely disposed faces of the jaws being disposed at an acute angle to each other, a wedge block to fit between and engage said faces, and means between the handle members and block for causing the latter to move lengthwise of the lugs to spread the same and move the jaws toward a closed position, when the handle members are contracted.

6. A structure as in claim 5 in which means is provided between the handles and arms for preventing outward turning of the handles on the arms beyond a certain position; the links being arranged to cause the wedge to be still engaged with the lugs when the handles are spread to their fullest extent and are in said certain position relative to the arms.

7. A structure as in claim 6, guide means being provided between the contracting faces of the wedge, and lugs to prevent lateral displacement of the block.

In testimony whereof I affix my signature.

JOHN W. RYAN.
